UNITED STATES PATENT OFFICE.

FREDERICK W. SCHNEIDER, OF BALTIMORE, MARYLAND, ASSIGNOR TO PITTSBURGH PLATE GLASS COMPANY, A CORPORATION OF PENNSYLVANIA.

PNEUMATIC PAINTBRUSH.

Application filed March 23, 1923. Serial No. 627,118.

To all whom it may concern:

Be it known that I, FREDERICK W. SCHNEIDER, a citizen of the United States, and a resident of Baltimore, in the county of 5 Baltimore City and State of Maryland, have made a new and useful invention in Improvements in Pneumatic Paintbrushes, of which the following is a specification.

The invention relates to pneumatic paint 10 brushes or air brushes, as they are often termed. It has for its principal objects the provision of an improved construction, (1) which can very readily be taken apart and cleaned; (2) in which the strain upon the 15 hand in operating the two triggers is reduced, and the air trigger is operated in starting ahead of the paint trigger, and in stopping, after the paint trigger, without the exercise of conscious effort to secure 20 this sequence; (3) having a simple form of air control with a minimum loss of pressure due to friction in the passage from the hose to the air nozzle; and (4) having a simple 25 form of outlet head for securing the shift from a round spray to a flat one with the latter positioned either in a vertical or a horizontal plane. One embodiment of the invention is illustrated in the accompanying drawings wherein:

30 Figure 1 is a side elevation of the device. Fig. 2 is a vertical section with one of the side plates removed. Fig. 3 is a side elevation of the discharge head with the cap and securing nut removed. Fig. 4 is a plan view 35 of the head. Fig. 5 is an end elevation of the head. Fig. 6 is a side elevation of the cap. And Fig. 7 is an end elevation of the cap.

Referring to the drawings, and particu- 40 larly to Fig. 2, the principal parts may be enumerated as follows:

1 is the discharge head provided with the air nozzle 2; 3 and 4 are side plates which fit over and enclose the air supply tube 5 and 45 paint supply tube 6; 7 and 8 are nuts by means of which the side plates are clamped together; 9 and 10 are the air line and paint line connections; 11 is the air admission valve operated from the trigger 12; 13 is 50 the paint admission valve operated from the trigger 14; and 15 is a cap clamped to the head 1 by means of the nut 16, such cap being provided with a pair of inclined supplemental air nozzles as hereinafter de- 55 scribed.

Air is supplied to the central nozzle 2 through the tube 5 and this supply of air is controlled from the valve 11 mounted for longitudinal movement in the connection 9 and yieldingly held in closed position by 60 means of the spring 17. The valve 11 has a stem 18 which is grooved so that when the valve is moved to the rear, the air passes freely along the stem and into the supply tube 5. Mounted for longitudinal move- 65 ment in the tube 5 is the operating tube 19 which carries at its rear end a relatively thin metal plate 20 so that the obstruction offered by this member to the flow of air through the tube is slight. This plate is 70 adapted to engage the end of the valve stem 18 when the tube 19 is moved to the left. The sides of the supply tube are slotted, as indicated at 21, and through these slotted sides projects a pin 22 carried by the tube 75 19 and adapted to be operated by the forked finger 23 at the upper end of the trigger 12. The arrangement, as above described, in- 80 cluding the valve 11, tube 19 and plate 20 provide for a straightaway air passage from the connection 9 to the nozzle 2, so that the losses in pressure due to friction are re- 85 duced to a minimum. Any leakage of air through the slots 21 is slight, as the tube 19 has a relatively close fit in the tube 5. 85

The needle valve 13 which controls the flow of the paint through the nozzle 24 is normally held forward by means of the spring 25 bearing at its rear end against the stuffing box 26 which constitutes a closure 90 for the cylinder 27 carrying the valve. The nozzle 24 is screw threaded into the end of the cylinder 27 which permits of its endwise adjustment to bring the outlet end to proper 95 position with respect to the nozzle 2, such nozzle 2 being adjustable and being held in position by means of the screw 28. The triggers 12 and 14 are carried upon pins 29 and 30 secured to the side plate 3 so that when the side plates are separated, the trig- 100 gers may be readily removed. The stem of the valve 13 is provided with a pair of nuts 31, one of which is a lock nut, which serve to adjust the amount of lost motion in the movement of the trigger 14. The paint sup- 105 ply tube 6 is preferably of flexible metal, screw threaded into the head at its forward end, as indicated at 32 and threaded to the connection 33 at its rear end as indicated at 34. 110

The foregoing arrangement, including the use of the side plates 2 and 3 provides a convenient arrangement for taking the device apart for cleaning or repair. In order to gain access to the interior of the device, all that is necessary is to unscrew the connections 9 and 10 and remove the clamping nuts 7 and 8 which leaves the side plates free to be removed. In order to prevent the supply tube 5 from being unscrewed at its forward end when the connection 9 is unscrewed, a sleeve 7^a is shrunk onto the tube 5, such sleeve having flat sides engaging the side plates 2 and 3, so that it cannot rotate. The air supply tube 5 and paint supply tube can then very readily be unscrewed to give access to the air and paint nozzles and to permit the cleaning of the pipes in case they become clogged. The arrangement of the two triggers is also advantageous, as it reduces the strain upon the hand of the operator, as compared with those constructions in which the two triggers are operated by the fingers. In the present device, the pressure of the palm or base of the hand operates the air trigger 12, while the pull of two of the fingers serves to operate the paint trigger. In operating these two triggers, it is desirable that the air trigger be operated first when the device is started and that the paint trigger be released first when the operation is discontinued. I have found that the pressure, as naturally applied by the operator upon the handle of the device, and without conscious effort, gives this desired sequence of operation. Pressure of the hand in starting the device first opens the air valve, after which the pull by the fingers opens the paint valve, while in the release operation, the relaxing of the hand first releases the paint trigger and then the air trigger. The operation of the device, therefore, requires less attention and skill than is the case in the type of apparatus where two finger triggers are used.

The air nozzle construction will be seen by reference to Figs. 3 to 7. Referring to these figures, it will be seen that the air head is provided with a conical surface 35 provided with an annular groove 36 and with four branch grooves 37 leading inward toward the center of the head from the groove 36. The groove 36 is supplied with air through a pair of inclined passages 38. The cap 15 is provided with an annular, conical surface 39 adapted to oppose and fit tightly against the annular surface 35 on the head. Leading from this surface are two passages 40 leading to the supplemental air nozzles 41. The cap 15 is held in position against the head by means of the nut 16 which fits over the end of the cap and has engagement with the threaded portion 42 of the head. When the cap is in a position of rotary adjustment such that the ends of

the passages 40 are out of alignment with the branch passages 37, the supply of air to the supplemental nozzles 41 is cut off, so that the only supply of air is through the central nozzle 2, thus giving the ordinary or round spray. If, however, the cap is rotated so as to bring the inner ends of the passages 40 over the branch passages 37, air is supplied to such passages 40 via the groove 36 and the branch passages and the spray of paint, which would otherwise be round, is spread laterally, giving a fan spray. When it is desired to turn this spray 90°, all that is necessary is to rotate the cap 90°, bringing the inner ends of the passages 40 into alignment with the other set of branch passages 37. When the cap is in its desired position of adjustment, the nut 16 is tightened sufficiently to prevent any accidental rotation of the cap. This forms a simple and convenient method of securing either a round spray, a vertical fan spray or a horizontal fan spray, depending upon the requirements of the work. The parts constituting the head may be easily taken apart for cleaning purposes. In case paints of different degrees of fluidity are used, paint nozzles similar to 24, but of different interior dimensions, may be substituted, thus rendering the device capable of a wide variety of use.

What I claim is:

1. In combination in a pneumatic air brush having a body portion, a paint nozzle and an air nozzle arranged in operative relation, supply passages leading to the nozzles, and valves for controlling said passages, of a pistol grip for the body portion, and a pair of triggers for operating the valves, one of such triggers extending along the back of the grip, and operable by the pressure of the palm or base of the hand of the operator, and the other lying forward of the grip and operable by the pull of one or more of the fingers of such hand.

2. In combination in a pneumatic air brush having a body portion, a paint nozzle and an air nozzle arranged in operative relation, supply passages leading to the nozzles, and valves for controlling said passages, of a pistol grip for the body portion, and a pair of triggers for operating the valves, the air controlling trigger extending along the back of the grip, and operable by the pressure of the palm or base of the hand of the operator, and the paint controlling finger lying forward of the grip, and operable by the pull of one or more of the fingers of such hand.

3. In combination in a pneumatic air brush, of a discharge head carrying air and paint nozzles, supply tubes leading rearwardly from said head, a pair of similar side plates fitting over and enclosing said tubes and including rear extension portions and grip portions, opposing semi-cylindrical

threaded parts at the ends of said portions fitting around said supply tubes, clamping nuts on said threaded parts for securing the tubes and side plates in assembled relation,

5 valves for controlling the flow through the tubes, and trigger means for operating the valves.

4. In combination in a pneumatic air brush, of a discharge head carrying air and 10 paint nozzles, supply tubes leading rearwardly from said head, a pair of similar side plates fitting over and enclosing said tubes and including rear extension portions and grip portions, opposing semi-cylindrical 15 threaded parts at the ends of said portions fitting around said supply tubes, clamping nuts on said threaded parts for securing the tubes and side plates in assembled relation, valves for controlling the flow through the 20 tubes, and a pair of triggers for controlling the flow through said tubes mounted between the side plates, the said supply tubes being detachably secured to said head.

5. In combination in a pneumatic air brush, of a discharge head carrying air and 25 paint nozzles, an air supply tube leading rearwardly from said head, a flexible paint supply tube leading rearwardly and laterally from said head and detachably secured thereto, a pair of similar side plates fitting over and enclosing said tubes, and including forward extension portions fitting around the forward ends of the tubes, rear extension portions fitting around the rear end of the air tube, and grip portions extending laterally fitting around the flexible paint tube, opposing semi-cylindrical threaded parts at the ends of the rear extensions and grip extensions, clamping nuts on said 30 threaded portions, valves for controlling the flow through the tubes, and trigger means for operating the valves.

6. In combination in a pneumatic air brush, of a discharge head carrying air and 35 paint nozzles, an air supply tube leading rearwardly from said head, a flexible

paint supply tube leading rearwardly and laterally from said head and detachably secured thereto, a pair of similar side plates fitting over and enclosing said tubes, and 50 including forward extension portions fitting around the forward ends of the tubes, rear extension portions fitting around the rear end of the air tube, and grip portions extending laterally fitting around the flexible 55 paint tube, opposing semi-cylindrical threaded parts at the ends of the rear extensions and grip extensions, clamping nuts on said threaded portions, valves for controlling the flow through the tubes, and trigger means 60 for operating the valves, the said air and supply tubes having threaded engagement with said head at their forward ends.

7. In combination in a pneumatic air brush, an air nozzle, a supply tube leading thereto and having a slot through its side, an air admission valve at the rear end of the tube opening by a rearward movement and yieldingly held forward in closed position, an operating tube slidably mounted 70 in the supply tube and adapted to open the air valve, a trigger, and means carried by the operating tube and projecting through said slot in the supply tube and adapted to be moved by the trigger.

8. In combination in a pneumatic air brush, an air nozzle, a supply tube leading thereto and having a slot through its side, an air admission valve at the rear end of the tube opening by a rearward movement and yieldingly held forward in closed position, a forwardly projecting stem on said valve, an operating tube slidably mounted in the supply tube and having a projection extending through the slot in the supply tube, means carried by the operating tube for engaging the stem of the valve, and a trigger for moving said projection.

In testimony whereof, I have hereunto subscribed my name this 5th day of March, 80 1923.

F. W. SCHNEIDER.
